UNITED STATES PATENT OFFICE.

FREDERICK MYERS, OF NEW YORK, N. Y.

SPROCKET-CHAIN.

SPECIFICATION forming part of Letters Patent No. 571,978, dated November 24, 1896.

Application filed June 15, 1896. Serial No. 595,539. (No model.) Patented in Canada June 23, 1896, No. 52,729.

To all whom it may concern:

- Be it known that I, FREDERICK MYERS, of the city, county, and State of New York, have invented certain new and useful Improvements in Sprocket-Chains, (for which I have received Letters Patent in Canada, No. 52,729, dated June 23, 1896;) and I do hereby declare that the following is a full, clear, and exact description of the same.
- 10 This invention has relation to sprocket-chains of the class in which the alternate links are similar and are connected by coupling-blocks, the links and the blocks being detachable one from the other.
- 15 The object of the invention is the provision of a strong and durable chain of the character described, the links of which can be readily coupled and uncoupled without the use of tools.
- 20 To these ends the invention consists in the improvements which I will now proceed to describe and claim.

Of the accompanying drawings, forming a part of this specification, Figure 1 represents 25 a perspective view of a piece of sprocket-chain embodying my invention. Fig. 2 represents a side view showing one of the coupling-links turned to position to permit the removal of the stud connecting it with the 30 accompanying link. Fig. 3 represents a section on line 3 3 of Fig. 2. Fig. 4 represents one of the studs.

The same letters of reference indicate the 35 same parts in all the figures.

My improved sprocket-chain is composed of links *a* and coupling-blocks *b*. Each link *a* is composed of two side straps *a'* *a'*, which are located side by side and parallel with each other, and cross-bars *a²* *a²*, connecting the 40 outer edges of said straps, the inner edges of the straps being disconnected, so that the straps are separated by an opening which is unobstructed at the inner edges of the straps and is obstructed only by the cross-bars *a²* *a²*, 45 said opening receiving the end portions of the coupling-blocks, hereinafter described, and the teeth of the sprocket-wheel, which enter the spaces between the ends of the coupling-blocks, the cross-bars *a²* *a²* being 50 preferably separated sufficiently to permit the sprocket-teeth to project between them.

Each side strap *a'* is provided with a longi-

tudinal slot *a³*, which has an enlargement *a⁴* at its central portion.

The coupling-blocks *b* are formed at their 55 end portions to enter the spaces between the side straps and are provided with outwardly-projecting transverse pintles *b'* *b'* at their end portions, which pintles are formed to closely fit the end portions of the slots *a³* and are 60 provided with heads or flanges *b²* of greater diameter than the width of the end portions of the slots *a³*, said heads bearing against the outer sides of the side straps *a'* and preventing said straps from spreading. The pintles 65 *b'* are formed upon studs *b³*, which are removably inserted in sockets *b⁴* *b⁴* in the coupling-blocks *b*.

The diameter of the enlarged portions of the slots in the link-straps is somewhat greater 70 than that of the studs *b³* and heads *b²*. Consequently by adjusting a block and the accompanying pintle-stud so that the stud will coincide with the enlarged portions of the slots in the link, as shown in Figs. 2 and 3, the 75 stud may be moved endwise into or out of the slots *a³* and sockets *b⁴*. It will be seen, therefore, that the parts of the chain can be readily assembled and as readily separated, and that when the said parts are in their operative relation to each other they cannot become disconnected.

I prefer to make the coupling-blocks of a plurality of separate plates placed side by side, as indicated in the drawings, the plates 85 being firmly secured together by any suitable means.

It will be seen that the described construction of the links enables them to be readily and cheaply made of sheet metal by striking 90 out a suitable blank from a flat sheet and bending the blank into the form shown.

The wear is sustained by the pintle-studs, these being separable from the other parts of the chain, so that they can be hardened to 95 any desired extent, it being feasible to equally harden the studs, the coupling-blocks, and the links.

The chain can be taken apart without the use of tools, and can therefore be very conveniently repaired by the rider in case of breakage of any of the parts, spare parts being carried.

The feature of the cross-bars *a²* is essential

to the practical success of the chain, as without them the links would twist to such an extent as to render the chain unfit for use. It will be seen that by my construction of chain 5 the disconnection of its parts is readily accomplished, while at the same time when the parts are assembled they are held firmly against any tendency to twist.

I claim—

- 10 1. A chain composed of links and coupling-blocks alternately coupled together, each link comprising two parallel straps provided with longitudinal slots which are centrally enlarged and cross-bars connecting the outer edges of said straps, their inner edges being disconnected, while the coupling-blocks have at their ends oppositely-projecting pintles to fit the ends of the slots and having heads which take over the outer sides of the straps
- 15 2. The diameter of said heads being less than that of the enlarged portions of the slots, substantially as and for the purpose described.
- 20 2. A chain composed of links and coupling-blocks alternately coupled together, each link

comprising two parallel straps provided with 25 longitudinal slots which are centrally enlarged, and cross-bars connecting the outer edges of said straps, their inner edges being disconnected, while the coupling-blocks have in their end portions removable studs the 30 ends of which form oppositely-projecting transverse pintles, which are formed to fit the end portions of the slots and have heads which engage the outer sides of the straps, the diameter of said studs and heads being 35 less than that of the enlarged portions of the slots, so that the studs are independently insertible and removable when in line with said enlargements.

In testimony whereof I have signed my 40 name to this specification, in the presence of two subscribing witnesses, this 8th day of June, A. D. 1896.

FREDERICK MYERS.
